UNITED STATES PATENT OFFICE.

LAWRENCE M. CARGO, OF PITTSBURG, PENNSYLVANIA, ASSIGNOR TO
GEORGE WESTINGHOUSE, OF SAME PLACE.

DESIGN FOR A LAMP-GLOBE.

SPECIFICATION forming part of Design No. 26,648, dated February 16, 1897.

Application filed January 11, 1897. Serial No. 618,881. Term of patent 14 years.

To all whom it may concern:

Be it known that I, LAWRENCE M. CARGO, a citizen of the United States, residing at Pittsburg, in the county of Allegheny and State of Pennsylvania, have invented or discovered a certain new and original Design for Glass Globes, of which the following is a specification.

The invention described herein relates to a certain new and original design for globes for electric and other drop lights, of which the following is a specification, reference being had to the accompanying drawings, showing in—

Figure 1 a side, and in Fig. 2 a sectional, elevation of the globe.

The leading features of the design consist

of a conical body portion, a groove at the neck or upper portion of the body, and the inwardly-curved lower portion or curtain. 20

The body 1 has the form of a truncated cone, having an externally-grooved neck 2. The lower portion of the body is curved, and this curvature is continued in the concavo-convex curtain portion 3. 25

I claim herein as my invention—

The design for globes substantially as shown and described.

In testimony whereof I have hereunto set my hand.

LAWRENCE M. CARGO.

Witnesses:

F. E. GAITHER,

DARWIN S. WOLCOTT.
